The ornamental design for an electronic atomization device, as shown and described.

DESCRIPTION

FIG. 1 is a first perspective view of an electronic atomization device;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof;

FIG. 8 is an enlarged bottom view thereof; and,

FIG. 9 is an enlarged view of a portion of area 9 circumscribed in FIG. 1.

The evenly-spaced broken lines in the drawings depict portions of the electronic atomization device that form no part of the claimed design; The long dash-short dash broken lines surrounding the enlarged detail views are for annotative purposes and form no part of the claimed design.
